United States Patent

Des. 236,637
Patented Sept. 2, 1975

236,637

CATHETER CONNECTOR

Edward G. Dykstra, East Aurora, and Frank P. Wilton,
Buffalo, N.Y., assignors to Ethylox Products, Inc.,
Buffalo, N.Y.

Filed Dec. 26, 1973, Ser. No. 428,030

Term of patent 14 years

Int. Cl. D24—04

U.S. Cl. D32—1

Fig. 1.

Fig. 2.

Fig. 3.

Fig. 4.

Fig. 5.

FIG. 1 is a side elevational view of the catheter connector of our new design;

FIG. 2 is a top plan view thereof;

FIG. 3 is a bottom plan view thereof;

FIG. 4 is an elevational view taken from the left-hand end of FIG. 1; and

FIG. 5 is an elevational view taken from the right-hand end of FIG. 1.

We claim:

The ornamental design for a catheter connector, substantially as shown.
